UNITED STATES PATENT OFFICE.

PAUL C. THAYER, OF QUINCY, CALIFORNIA.

TRAP.

1,226,924.

Specification of Letters Patent.

Patented May 22, 1917.

Application filed February 12, 1917. Serial No. 148,162.

To all whom it may concern:

Be it known that I, PAUL C. THAYER, a citizen of the United States, residing at Quincy, in the county of Plumas and State 5 of California, have invented certain new and useful Improvements in Traps; and I do declare the following to be a full, clear, and exact description of the invention, such as will enable others skilled in the art to 10 which it appertains to make and use the same.

My invention has for its object to improve upon the construction shown in my U. S. Patent No. 1,186,297, of April 20, 1915, the 15 improvements residing particularly in the keeper and trigger for holding the jaws in set position.

With the foregoing general object in view, the invention resides in the novel features of 20 construction and unique combinations of parts to be hereinafter fully described and claimed, the descriptive matter being supplemented by the accompanying drawings which constitute a part of this application, 25 and in which:

Figure 1 is a side elevation of the improved trap showing the same set for use;

Fig. 2 is a top plan view;

Fig. 3 is an enlarged vertical section 30 showing more particularly the arrangement of the keeper and trigger when the trap is set;

Fig. 4 is a similar view showing the position of the trigger when releasing the 35 keeper; and

Fig. 5 is a perspective view of the trigger.

In the drawings above briefly described, the numeral 1 has reference to a support preferably in the form of a flat circular 40 block having a plurality of deep grooves 2 spaced apart and shallow grooves 3 connecting them. Coiled springs 4 are partially received in the grooves 2 and a clamping band 5 passes through said springs and 45 is received in the grooves 3 for holding them in place, one end of each spring being rigidly secured to the block 1, while the other end thereof is extended to form a jaw 6 preferably of the hook shape shown in the 50 drawings. Arms 7 are pivoted at one end to the jaws 6 and are adapted to extend beyond the inner ends thereof for engagement with the keeper 8 which is mounted at the center of the block 1, the top of the

block being preferably provided with a 55 metal covering 9 to reinforce it and to prevent injury from the arms 7.

The lower side of the block 1 is formed with a cavity 10, while an opening 11 leads from this cavity through the upper side of 60 the block, the lower end of said cavity being closed by a metal plate 12 which extends over the lower side of the block. It is within the opening 11 that the keeper 8 is pivoted upon a horizontal pivot pin 13, said 65 keeper being of inverted L-shape with its vertical arm 13' extending through an opening in the plate 9, into the opening 11 and cavity 10, while the horizontal arm 14 of said keeper overlies plate 9 and receives 70 thereunder the arms 7. An abutment in the form of a vertically disposed plate 15 extends across the opening 11 and forms with one side thereof a guide which receives the 75 upper end of the trigger 16 whose construction is shown most clearly in Fig. 5. The vertical arm 13 of the keeper 8 is adapted to be swung into contact with one side of the abutment 15 and to be held in this position by a depressed seat 17 which is formed on 80 and opens toward the upper end of the trigger 16. It will thus be obvious that when this trigger is pulled downwardly, the keeper 8 will be permitted to rock around its pivot 12 to release the arms 7, whereupon 85 the springs 4 will move the jaws inwardly to a common point beneath the block 1.

The keeper 16 is preferably formed of a single length of stiff wire disposed vertically and having substantially its upper half bent 90 downwardly at 18 to form a spring seat, and then upwardly to provide the seat 17, said upper half extending an appreciable distance above said seat 17 and being here bent downwardly at 19 so that a loop-shaped 95 vertical stem is provided which is received slidably between the abutment 15 and the adjacent wall of the opening 4. The lower half of the wire extends slidably through an opening in the plate 12 and is bent into 100 the form of a hook 20 upon which the bait is hung. A coiled spring 21 is located in the cavity 10 and bears at its lower end on the plate 12, the upper end of said spring being received in the seat 18 above described. The tension of this spring is thus exerted to yieldably retain the trigger in 105 operative position after it is once set, but

this tension is insufficient to prevent an animal from tripping the device.
From the foregoing taken in connection with the accompanying drawings, it will be obvious that several changes have been made over the construction shown in the patent above referred to, all of these changes serving to increase the efficiency of the trap although they are themselves simple and do not increase the expense of manufacture.

I claim:

1. A trap comprising a jaw and means for impelling it to operative position, a support having a guide, a keeper mounted on said support for holding the jaw in set position, and a trigger mounted slidably in said guide and having a depressed seat opening toward one of its ends and normally receiving a part of said keeper to hold the latter in operative position; in combination with means for co-operation with said jaw in trapping the prey.

2. A trap comprising a jaw and means for impelling it to operative position, a support having a guide, an abutment adjacent said guide, a pivoted keeper for holding the jaw in set position, said keeper having a portion to swing against said abutment, and a trigger mounted slidably in said guide and having a depressed seat opening toward one of its ends to receive said abutment and said portion of the keeper to retain the latter in operative position; in combination with

means for co-operation with said jaw in trapping the prey.

3. A trap comprising a jaw and means for impelling it to operative position, a support having a guide, an abutment adjacent said guide, a pivoted keeper for holding the jaw in set position, said keeper having a portion to swing against said abutment, a trigger formed of a single length of wire having one of its ends bent toward its other to form a spring seat and then bent in the opposite direction to form another seat, the portion of the wire beyond the open side of the last named seat being slidably received in said guide while the other end portion of said wire constitutes a bait support, said last named seat being adapted to receive therein the abutment and said portion of the keeper to retain the latter in operative position, and a coiled spring having a portion received in the aforesaid spring seat, said spring operating to yieldably hold the trigger in set position; in combination with means for co-operation with said jaw in trapping the prey.

In testimony whereof I have hereunto set my hand in the presence of two subscribing witnesses.

PAUL C. THAYER.
